TRAIN ORDER HOLDER

Lawrence W. Compton, Boardman, Oreg.

Application January 9, 1936, Serial No. 58,368

7 Claims. (Cl. 258—2)

This invention relates to a train order holder. It is aimed to provide a novel construction which may hold a plurality of train order hoops permitting removal thereof one at a time, and adjustment of the parts expeditiously after each removal, to hold the remainder of the hoops against accidental displacement.

It is further aimed to provide a novel structure having relatively slidable parts to position the holders, one of which parts has displaceable elements to permit an engaged hoop to be expeditiously removed.

The more specific objects and advantages will become apparent from a consideration of the description following in connection with accompanying drawing illustrating an operative embodiment.

In said drawing:—

Figure 1 is a view of the invention in side elevation;

Figure 2 is a view of the upper part of the device taken at a right angle to Figure 1;

Figure 3 is a rear elevation of the upper part of the device;

Figure 4 is a longitudinal sectional view taken on the line 4—4 of Figure 2;

Figure 5 is a cross sectional view taken on the line 5—5 of Figure 2;

Figure 6 is a cross sectional view taken on the line 6—6 of Figure 2;

Figure 7 is a vertical sectional view taken on the line 7—7 of Figure 2;

Figure 8 is a cross section taken on the line 8—8 of Figure 2; and

Figure 9 is a diagrammatic view of the electrical connections.

Referring specifically to the drawing wherein like reference characters designate like or similar parts, 10 designates a staff having longitudinal grooves 11, in the opposite sides thereof. A plurality of train order holding loops are provided at 12, having bases or bars 13 at one end which are identical in cross section with the staff 10, therefore having the grooves 14 in opposite sides thereof. Any desired number of the loops 12 may be used in the apparatus according to the height thereof, and for instance, four as shown in the drawing. Said loops preferably at bars or bases 13 have spring clasps 13', adapted to hold the orders removably in place in the holders or loops, but so that they may be readily grasped and removed.

Slidable relatively to the staff 10 is a follower section 15, preferably having side members 16, bolted at 17 to a rear member 18. These side

members 16, have inwardly extending ribs 19, arranged to engage and slide in the grooves 11 and 14.

Said side members 16 have sections 15' in line therewith, and have greater length than the length of the bars 13. Spring hinges 20 connect the sections 15' to the rear element 18 and they normally urge such sections 15' to the closed or full line positions shown in the drawing. However, they will automatically yield to enable the uppermost hoop to be withdrawn, upon that hoop being moved to the right or to the left, as suggested by the dotted line in Figure 5.

A bumper or cushioning element 21, is engaged by the uppermost bar 13, and such member is carried by a rod 22, slidable in a cap portion 23, on the rear member 18 of follower section 15. Said cap 23 is recessed as at 24 to accommodate an expansive spring 25, curled about the rod 22 and engaging an abutment 26 on such rod. In order to facilitate upward movement or retraction of the bumper 21 when filling the device with the train order loops, a knob 27 is attached to the upper end of such rod.

It will be noted that each of the displaceable sections 15' carries a lamp box 28 in which a reflector 29, is disposed. Associated with each reflector is an electric lamp 30. In order to illuminate the lamp 30, a suitable electric battery 31 is carried by the section 15. The lamps 30, are wired to said battery by conductors 31', so as to be in parallel therewith and in the event one of them burns out, the other will continue to burn. Such conductors include a suitable switch 32. It will also be noted that the conductors 31 include the hinges 20, as their movable parts. Thus a very durable and rigid construction, not likely to get out of order, notwithstanding the movement of the sections 15', is provided.

A handle 33 is provided on the slidable section 15.

It will be understood that the train orders are held in place by the spring clips 13', and that the loops or hoops 12 are in pluralities and are releasably secured in place as shown in the drawing. The bars 13 are arranged end-to-end and on top of the staff 10. Upon the detachment of the uppermost hoop, the displaceable section 15', according to the direction of movement of the hoop, will be automatically moved to release it. Thereupon, the handle 33 may be depressed to arrange the abutment 21 on top of the adjacent bar 13, through depression of the handle 33 and section 15. Such movement will dispose the sections 15' opposite the bar 13 of the leading upper-

most hoop so that the same may be removed, after which, the foregoing action may be repeated, to permit removal of the hoop there below, etc.

5. Various changes may be resorted to provided they fall within the spirit and scope of the invention.

I claim as my invention:—

1. A device of the class described to releasably hold hoops having a retaining groove, a staff on which a hoop is disposable having a groove, a section slideable on the staff and having a projection entering said groove, said section having a displaceable part to permit release of the uppermost hoop.

2. A device of the class described, comprising a staff, a member slidably mounted on said staff, said member being adapted to accommodate a plurality of bars arranged end to end and each having a hoop thereon, said bars being collectively impelled in said member by engagement with said staff, and displaceable means on said member to permit removal of one of said hoops and bars therefrom.

25. 3. A device of the class described to releasably hold hoops having a retaining groove, a staff on which a hoop is disposable having a groove, a section slideable on the staff and having a projection entering said groove, said section having a displaceable part to permit release of the uppermost hoop, and bumper means carried by the section for engagement with the upper end of the uppermost hoop.

4. A device of the class described to releasably hold hoops having a retaining groove, a staff on which a hoop is disposable having a groove, a section slideable on the staff and having a projection entering said groove, said section having a displaceable part to permit release of the uppermost hoop, and bumper means carried by the section for engagement with the upper end of the uppermost hoop, an electric lamp carried by said displaceable parts, and electric circuit

means for said lamp including hinges, said hinges mounting said parts.

5. A device of the class described comprising a staff having a groove in opposite sides thereof, hoops having bars adapted to a line with said staff and having grooves to align with the first mentioned groove, a slideable section telescoped over said staff and bars having projections engaging the grooves of the staff and bars, said section having movable parts opposite the uppermost bar and displaceable to enable the bar to be withdrawn.

6. A device of the class described comprising a staff having a groove in opposite sides thereof, hoops having bars adapted to align with said staff and having grooves to align with the first mentioned groove, a slideable section telescoped over said staff and bars having projections engaging the grooves of the staff and bars, said section having movable parts opposite the uppermost bar and displaceable to enable the bar to be withdrawn, spring hinges maintaining said parts normally closed, and resiliently mounted means engaging the upper end of the uppermost bar.

25. 7. A device of the class described, comprising a staff having a groove in opposite sides thereof, hoops having bars adapted to align with said staff and having grooves to align with the first mentioned groove, slideable section telescoped over said staff and bars having projections engaging the grooves of the staff and bars, said section having movable parts opposite the uppermost bar and displaceable to enable the bar to be withdrawn, spring hinges maintaining said parts normally closed, and resiliently mounted means engaging the upper end of the uppermost bar, the lamp boxes carried by said parts, electric lamps for said boxes, and electric circuit means for said lamps passing through said hinges, a handle for the section, and said circuit including a battery on said section.

LAWRENCE W. COMPTON.
